(57) **CLAIM**

The ornamental design for a linen truck, as shown and described.

DESCRIPTION

FIG. 1 is an isometric view of a linen truck showing our new design;

FIG. 2 is a front view thereof;

FIG. 3 is a back view thereof;

FIG. 4 is a top view thereof;

FIG. 5 is a bottom view thereof; and,

FIG. 6 is a right side view thereof, the left side being a mirror image.

The broken lines in the figures represent portions of the linen truck that form no part of the claimed design.
